CLAIM

The ornamental design for a lazy Susan with refrigerated compartment, as shown and described.

DESCRIPTION

FIG. 1 is a side elevational view of a lazy Susan with refrigerated compartment, showing my new design.

FIG. 2 is a top plan view thereof.

FIG. 3 is a bottom plan view thereof.

FIG. 4 is a top plan view, with the lid removed; and FIG. 5 is a vertical sectional view taken through the medial plane thereof.

FIG. 1

FIG. 3

FIG. 5
